UNITED STATES PATENT OFFICE.

JAMES McDOWELL WHITESIDE, OF BANGOR, IRELAND.

STRUT FOR FLOOR JOISTS.

Application filed January 14, 1924. Serial No. 685,997.

To all whom it may concern:

Be it known that I, JAMES McDOWELL WHITESIDE, a resident of 36 Ward Avenue, Bangor, County Down, Ireland, a subject of the King of Great Britain and Ireland, have invented certain new and useful Improvements Relating to Struts for Floor Joists, of which the following is a specification.

This invention relates to strengthening struts for floor joists also uprights for walls and wood-frame structures. Usually wood floor joists and wall framing are strengthened in the case of floors by means of what is called herring-bone strutting, consisting of crossed wooden struts suitably shaped at their ends and placed between the joists to which they are secured by nails at their ends and in the case of wall frames by solid bridging. This involves considerable labour as, for example, the crossed wooden struts have to be cut at their ends and then saw-cut to receive the nails so as to prevent them splitting when they are being placed in position and the nails are being driven. This has to be very carefully done, and even then is not always satisfactory as the wooden struts often split and they are subject to shrinkage which, in time, allows the joists to spring and vibrate on the wall plates.

It is the object of the present invention to make a crossed strut or trussing out of metal which shall be light in weight, strong for its weight, easily adjusted and rapidly fixed in position, readily packed in small space for transit, and shall be simply and cheaply manufactured. My strut, especially if stamped from sheet metal, satisfies all these requirements; further, its parts are reversible in manufacture, only one pattern being required.

The invention is shown by way of example on the annexed drawing.

Fig. 1 is a view of the crossed metal strut.

Fig. 2 shows a number of the crossed metal struts in position.

Fig. 3 shows the crossed metal struts used in a wall framing.

Referring to the drawings:—

The crossed metal struts comprise two steel angle bars 1 and 2 with the respective vertically disposed sides 1^a and 2^a riveted

together whilst the other sides 1^b and 2^b have each one end bent down and the other end bent up. The upwardly bent ends 1^c and 2^c are shown at the top whilst the downwardly bent ends 1^d and 2^d are at the bottom in each case, when the strut is in position. Holes are provided in the portions 1^c, 2^c, 1^d and 2^d for the nails which secure the strut to the joists 3 as shown at Fig. 2.

The steel angle members forming the metal reinforcing struts instead of being crossed as shown could be arranged for transportation with the two abutting flanges, or sides 1^a and 2^a lying alongside each other so as to take up as little room as possible and when being placed in position it is only necessary to open them out into cross formation shown at Fig. 1 and to the extent desired to bring the ends to the required positions on the sides of the joists for securing the struts in position.

The advantages of the steel struts are, that they are cheap and easy to manufacture, they are easily fixed in position and, owing to the bent up ends being more or less resilient, they allow for the struts being drawn tightly into position. The steel struts are also proof against shrinkage and dry rot. The steel struts have the further advantage of being suitable for different heights of joists and it is believed that one size of the metal struts would serve for joists of 8, 9, and 10 inch depth and similarly another size would serve for 11, 12, and 13 inch joists and so on.

The example shown at Fig. 3 of a vertical frame for a building or other structure has the metal reinforcing struts arranged in line. They may if desired be otherwise arranged and could be staggered after the manner of solid bridging used for vertical structures.

What I claim as my invention and desire to secure by Letters Patent is:—

1. A collapsible crossed strut or trussing for floor joists and the like having in combination two metal angle bars pivoted together, and having a side of each angle bar at each end thereof bent parallel with the adjacent joist and orificed to receive an attaching member such as a nail.

2. A collapsible crossed strut or trussing

for floor joists and the like comprising in combination two metal bars of L-shape in cross section having the base of each L bent at each end parallel with the adjacent joist, 5 and orificed to receive an attaching member such as a nail, and having the two uprights of the L's pivoted together, and each cut at one end to abut against the adjacent joist

and at the other end against the bent part of the base.

10

In testimony whereof I affix my signature in presence of two witnesses.

JAMES McDOWELL WHITESIDE.
